UNITED STATES PATENT OFFICE.

ALBERT T. MARSHALL, OF SWAMPSCOTT, MASSACHUSETTS, ASSIGNOR
TO FEDERAL AUTOMATIC REFRIGERATING CO., OF NEW YORK, N. Y.,
A CORPORATION OF NEW JERSEY.

EXPANSION-VALVE FOR REFRIGERATING APPARATUS.

SPECIFICATION forming part of Letters Patent No. 785,265, dated March 21, 1905.

Application filed March 4, 1904. Serial No. 196,481.

To all whom it may concern:

Be it known that I, ALBERT T. MARSHALL, a citizen of the United States, residing at Swampscott, in the county of Essex and State 5 of Massachusetts, have invented a new and useful Expansion-Valve for Refrigerating Apparatus, of which the following is a specification.

This invention relates to an automatically-controlled valve for regulating the admission 10 of anhydrous ammonia or other refrigerating medium to the expansion-coils of a refrigerating apparatus.

The especial object of this invention is to provide a strong, simple, and inexpensive expansion-valve in which a needle-valve control 15 is obtained by means of parts which are self-centering and are not liable to be twisted or turned out of coöperative relation and in which all moving parts are completely inclosed.

To these ends this invention consists of the automatic expansion-valve for refrigerating apparatus and of the combinations of parts therein, as hereinafter described, and more particularly pointed out in the claims at the 25 end of this specification.

In the accompanying drawings, Figure 1 is a sectional view of an automatic expansion-valve for refrigerating apparatus constructed according to this invention, and Fig. 2 is a 30 diagrammatic view of sufficient parts of a refrigerating apparatus to illustrate the application of my expansion-valve thereto.

In United States Letters Patent No. 549,426, granted November 5, 1895, in the name of 35 Alexander T. Ballantine, a refrigerating apparatus is disclosed which employs an expansion-valve of the same type as the valve forming the subject-matter of this invention. The especial object of this invention is to improve 40 the construction shown in this patent by providing an automatic valve in which the moving parts are inclosed within the casing and in which the valve-stem and valve-seat are carried by parts which are self-centering and are 45 fastened in place to insure the maintenance of correct coöperative relation.

Referring to the drawings for a detail description of an expansion-valve constructed

according to this invention, as shown in Fig. 2, A designates the reservoir or chamber for containing the liquefied refrigerating medium. From the chamber A the refrigerating medium passes through the expansion-valve V to the expansion-coil C. From the expansion-coil C the ammonia or other refrigerating medium is drawn by a pump P, which may be run by a motor M, and the ammonia is compressed in condensing-coils D, which may be inclosed in a tank, so that the cycle is completed by the return of the liquefied ammonia to the storage-chamber.

The expansion-valve, as illustrated most clearly in Fig. 1, consists, essentially, of a diaphragm-chamber formed by two castings or pieces 10 and 11. The castings 10 and 11 are clamped together by bolts 12, so as to fasten 55 between them an ordinary flat disk diaphragm. Extending through the diaphragm is a center screw 13, having an annular pocket for receiving the lower end of the spring 14. 60 The spring 14 is compressed by a collar 15, which is held from turning by a tongue or key 16 fitting into a vertical groove 17. Threaded into the nut 15 is an adjusting-screw 18, which extends up through a suitable stuffing-box or gland and is provided at its upper end with a wrench-section for turning or adjusting the same when it is desired to regulate 65 the feed of the refrigerating medium or the pressure at which the valve will close.

The expansion-valve may be supported in a bracket 19, in which the section 10 is fastened by small clamping-bolts.

The lower section 11 of the valve-casing is provided with opposed bosses or enlargements, which are bored out in line with each other. Extending transversely through the lower section 11 of the valve-casing is a pipe 20, which has both an inlet-passage and an outlet-passage for the refrigerating medium. 85 As shown, the transverse pipe 20 is preferably made by boring out a rod to provide an inlet-passage 21, which terminates in a downwardly-facing valve-seat, and also by boring out the pipe 20 to form the outlet-passage 22. 90 By means of this construction a single pipe is

used both for the inlet and outlet passages of the valve.

In the use of an expansion-valve of this type it is especially important that the valve-seat 5 should be held from twisting or turning, and I accomplish this purpose by providing the pipe 20 with a collar 23, having an extending pin engaging a socket drilled in the valve-casing 11. This forms, in effect, a simple and efficient construction for keying or locking the pipe 20, so as to hold the same from turning.

Threaded onto the center screw 13, which extends down through the diaphragm, is a 15 plunger or operating-piece 24. This plunger is cylindrical in form and is guided by the side walls of the valve-casing 11, although it is preferably fitted somewhat loosely therein. By fitting the piece 24 loosely in the valve-casing 20 11 a sufficient space is left so that the outlet pressure will act on the under side of the diaphragm. The plunger or operating-piece 24 is provided with a transverse cylindrical hole 25, through which the pipe 20 passes. Threaded into the plunger or piece 24 is a valve-stem 26, which is locked in place by a lock-nut 27. By means of this construction the valve-stem will be freely enough mounted to be self-centering, while at the same time the plunger will 25 30 be guided in its up-and-down movement by the side walls of the valve-casing. In actual practice I have found that this provides a cheap and reliable self-centering valve-stem.

The lower end of the casing 11 is closed by 35 a packing-collar or washer, which is fastened in place by a bottom-cap 28.

I am aware that changes may be made in the proportions and details of parts of an automatic expansion-valve constructed according 40 to this invention without departing from the scope thereof as expressed in the claims. I do not wish, therefore, to be limited to the form I have herein shown and described; but

What I do claim, and desire to secure by 45 Letters Patent of the United States, is—

1. As an article of manufacture, an automatic expansion-valve for refrigerating apparatus comprising a diaphragm-casing, a diaphragm mounted therein and acted upon on

one side by the pressure of the refrigerating medium, and upon the other side by a spring inclosed within the diaphragm-casing and tending to move the diaphragm in the opposite direction, a pipe extending transversely into the diaphragm-casing and containing both the inlet and outlet passages for the refrigerating medium, a collar upon the pipe with a pin extending therefrom which engages a socket in the casing to hold the pipe from turning, an operating-piece or plunger extending down from the diaphragm, said operating-piece or plunger having a cylindrical hole through which the pipe passes, and a valve-stem threaded into the operating-piece and having a pointed valve at its upper end 60 so as to be self-centering with respect to its valve-seat.

2. As an article of manufacture, an automatic valve for refrigerating apparatus comprising a diaphragm-casing, a diaphragm 70 mounted therein and acted upon on one side by pressure of the refrigerating medium, a coiled spring inclosed within the diaphragm-casing and tending to move the diaphragm in the opposite direction, an adjusting-collar for 75 said spring and having a key engaging a slot extending part way through the walls of the diaphragm-casing, a pipe extending transversely into the diaphragm-casing and containing both the inlet and outlet passages for 80 the refrigerating medium, a collar on the pipe with a pin extending therefrom and engaging a socket in the casing to prevent the pipe from turning, an operating-piece or plunger extending down from the diaphragm, said operating-piece or plunger having a cylindrical hole 85 through which the pipe passes and a valve-stem threaded into the operating-piece and having a pointed valve so as to be self-centering with respect to the valve-seat. 90

In testimony whereof I have hereunto set my hand in the presence of two subscribing witnesses.

ALBERT T. MARSHALL.
